US0D1098683S

(12) **United States Design Patent** (10) **Patent No.:** **US D1,098,683 S**
(45) **Date of Patent:** **** Oct. 21, 2025**

(54) **SHOE**

(71) Applicant: **adidas AG**, Herzogenaurach (DE)

(72) Inventor: **Mark Miner**, Los Angeles, CA (US)

(73) Assignee: **adidas AG**, Herzogenaurach (DE)

(**) Term: **15 Years**

(21) Appl. No.: **29/926,866**

(22) Filed: **Feb. 1, 2024**

Related U.S. Application Data

(62) Division of application No. 29/888,587, filed on Apr. 3, 2023, now Pat. No. Des. 1,021,361, which is a division of application No. 29/728,264, filed on Mar. 17, 2020, now Pat. No. Des. 1,009,412.

(30) **Foreign Application Priority Data**

(57) **CLAIM**

The ornamental design for a shoe as shown and described.

DESCRIPTION

FIG. 1 is a lateral side view of a shoe.

FIG. 2 is a medial side view of the shoe of FIG. 1.

FIG. 3 is a front perspective view of the shoe of FIG. 1.

FIG. 4 is a back perspective view of the shoe of FIG. 1.

FIG. 5 is a top perspective view of the shoe of FIG. 1.

FIG. 6 is a bottom view of the shoe of FIG. 1; and,

FIG. 7 is a lateral side front perspective view of the shoe of FIG. 1.

The even dashed broken lines surround portions of the shoe that form no part of the claimed design. The translucent shaded portions of the shoe shown inside the perimeter of the even dashed broken lines form no part of the claimed design.

1 Claim, 7 Drawing Sheets
